UNITED STATES PATENT OFFICE.

OLAUS C. WOLD, OF CHICAGO, ILLINOIS.

FOUNTAIN-PEN.

1,009,612.

Specification of Letters Patent. Patented Nov. 21, 1911.

Application filed May 16, 1911. Serial No. 627,449.

To all whom it may concern:

Be it known that I, OLAUS C. WOLD, a citizen of the United States, residing at Chicago, in the county of Cook and State of Illinois, have invented certain new and useful Improvements in Fountain-Pens, of which the following is a specification.

This invention relates to a type of fountain pen having relatively wide nibs and, therefore, especially adapted for producing wide lines. It is well adapted, for example, to lettering operations in which the letters are to be shaded so that their vertical portions are broad while their horizontal portions are narrow.

In carrying out my present invention, I provide a pair of relatively broad nibs and a suitable mounting therefor, and a fountain mechanism for delivering ink from a well to a point between the nibs, so as to secure a proper flow of ink at all times.

I am familiar with a form of fountain pen similar to the general class above described, but the same is restricted to a form of mechanism in which the ink is delivered through a tube extending at right angles to the lower nib of the pen, and which tube passes through the upper nib. I have found that this construction is open to a number of serious objections; and, as will herein-after appear, my present invention relates particularly to a type of construction in which the ink is delivered through a tube extending parallel to the nibs.

Objects of the present invention are, to provide a form of pen having the discharge tube from the well extending in a direction parallel to the nibs; to provide means for controlling the opening of the orifice of said tube independently of pressure on the nibs, so that the flow of ink will always be under the control of the operator; to provide, nevertheless, a type of construction which may be adapted for use with a mechanism which will automatically control the flow of ink; to provide a construction of pen such that the nibs can be easily inserted or removed independently of any other mechanism, thus enabling me to use different widths of nibs in the same pen body; to provide a type of mechanism such as will insure a perfect and positive closing of the ink orifice; and in other ways and manners to generally improve the type of this class of pen.

Other objects and uses will appear from a

detailed description of the invention, which consists in the features of construction and the combination of parts hereinafter described and claimed.

Referring to the drawings, Figure 1 shows a side view of the preferred form of pen, the rear portion of the handle being cut away; Fig. 2 shows an enlarged detail cross section of the front part of the pen of Fig. 1; Fig. 3 shows an enlarged detail elevation of the front part of the pen with the nibs deflected by pressure into working position; Fig. 4 shows a cross section taken on line 4-4 of Fig. 3, looking in the direction of the arrows; Figs. 5, 6 and 7 show three sets of nibs, each of different width, but all adapted for use in the pen of Fig. 1; Fig. 8 is an enlarged detail side view of the front part of a pen similar to that of Fig. 1, but provided with mechanism for automatically opening the ink orifice when the nibs are deflected by pressure; Fig. 9 is a plan view of the pen of Fig. 8; Fig. 10 is a view similar to Fig. 8, the nibs being deflected up into working position, however; and Fig. 11 is a greatly enlarged detail of a modified form of finger operating mechanism.

As heretofore stated, I am familiar with a form of fountain pen, the ink delivery tube of which extends downwardly toward the lower nib, so that the orifice faces the same, and so that the mechanism for opening and closing the orifice must extend in a direction perpendicular to the nibs. Such a form of construction has a number of disadvantages, chief among which is that it is difficult, if not impractical, to provide a mechanism for controlling the opening of said orifice at any and all times by hand. In the embodiment of my present invention, I preferably use the handle of the pen itself as the ink well and carry the ink delivery tube straight out from the same to a point between the nibs. This being the case, considerably more space is available for controlling the opening of said orifice than it would otherwise be possible to secure. Furthermore, it is possible, with such an arrangement, to provide means whereby the operator can at all times control the flow of ink.

While I have heretofore stated that in my present invention I provide an ink delivery tube parallel to the nibs, and not at right angles thereto, I do not intend to be limited to a construction in which the orifice itself

is parallel to the nibs, but rather to a construction in which the tube from the ink well to said orifice extends parallel to the nibs and preferably between them.

5 Referring now particularly to Figs. 1, 2 and 3, the handle of the pen is designated by the numeral 17. It is hollow so that it may serve as an ink well 18; and into its forward portion 19 is threaded a cap member 20, shouldered at 21 to secure a tight joint against the handle. The rear portion 22 of this cap is counterbored to provide a conical opening which gradually tapers down to a tubular opening 23. The extreme forward end of the cap is extended out as an elongated delivery tube 24, the orifice 25 of the opening being counterbored so that it may be tightly closed by a needle. A sleeve 26 fits loosely over the delivery tube portion 24, its forward end 27 carrying a needle 28, which extends inwardly to close the orifice when the sleeve is drawn back into the position shown in Fig. 2. The lower portion of the sleeve is 25 cut away at 29, directly underneath the needle, so that, when the sleeve is thrown forward, the ink may drop down to the lower nib 30 of the pen. A bell-crank 31 is pivoted to a lug 32 on the forward top portion of the cap, the horizontal arm of said bell-crank being suitably formed to provide a finger piece 33, which is normally thrown up by a spring 34. Two collars 35 and 36 are formed on the inner end 30 of the sleeve, the vertical arm or finger 37 of the bell-crank engaging the space between said collars. Obviously, depression of the finger piece serves to throw the sleeve forward and open the ink orifice. The writing portion of the pen comprises upper and lower nibs 38 and 30 respectively. These are curved together in their rear portions 39 until they finally meet to form a pair of flat fingers 40, the two nibs being preferably soldered together in said finger portions. An elongated hole extends inwardly into the cap on each side of the sleeve to receive one of the fingers 40, whereby the nibs are held in position on the pen. The fingers may have such a snug fit in said holes that the nibs are held in position without the necessity of any additional mechanism. It is evident that means should be provided for preventing the sleeve from rotating about the tube 24, as otherwise the hole 29 in the front end of the sleeve might eventually be turned so as to face upward. In the present instance, I so relate the nibs to the sleeve that the nibs perform this additional function of preventing rotation of the sleeve. To this end both of the nibs are cut away to provide an elongated slot 41, and the fingers straddle the sleeve. I then flatten the vertical portions 42 of the sleeve 60 to such an extent that the same cannot ro-

tate when once the fingers of the nibs have been properly inserted within the cap. This construction is well illustrated in Fig. 4. In order to remove the sleeve for replacement or repair, it is first necessary to pull out the nibs; after this the sleeve can be rotated through a quarter revolution and the arm 37 of the bell-crank may then be disengaged from the groove between the collars 35 and 36. Thereafter, the sleeve may 75 be slipped off from the tube 24 endwise. When in use the nibs of the pen will be deflected over approximately into the position shown in Fig. 3, and the ink will be deposited on the lower nib, when it will run 80 down into the angle 43 between the nibs. The operator, by depressing the finger piece 33 from time to time, can regulate the flow of ink, thus placing the mechanism entirely under his control. As the ink runs out from the well, air must be allowed to enter the same and occupy the space thus vacated. To this end, a tip 44 is threaded into the rear end 45 of the handle, as illustrated in Fig. 1. A fine tube 46 projects downwardly 90 from said tip and allows air to pass into the well through a hole 47 in the tip. In use, it would not be customary to fill the well entirely full of ink. This being the case, the tube 46 would project upwardly beyond 95 the surface of the ink, in case the pen were held with the nibs extending upwardly, so that the ink would not be spilled out through the tube and the hole 47.

In Figs. 8 to 10 inclusive, I illustrate a 100 construction similar to that of Figs. 1, 2 and 3, in that the sleeve is stationary, the needle being movable, but in the present instance an auxiliary mechanism is provided for automatically controlling the flow of 105 ink as the nibs are deflected by pressure. To this end a lever 70 is pivoted to the lug 71 on the forward end of the cap, its outer arm being provided on its lower face with a pair of lugs 72 adapted to engage a collar 110 73 on the sleeve; so as to control both in and out movements of said collar. The outer arm of the lever extends outwardly to a point substantially over the center of the upper nib, at which point it carries a set 115 screw 74. The latter may be so adjusted that as the nibs are deflected into the position shown in Fig. 10, the sleeve will be thrown out to allow a flow of ink. A leaf spring 75 tends to restore the sleeve to its normal 120 closed position. In order to permit independent control of the ink flow, the lever may be provided with a finger piece 76, in which case its operation would be similar to that of the construction shown in Figs. 125 1, 2 and 3.

In Fig. 11 is shown a construction substantially the same as that of Fig. 8, with the exception that the set screw arm of the lever is removed, thus making the operation 130

entirely independent of the movement of the nibs.

Referring particularly to Figs. 2, and 11, it will be noted that the tip of the lower nib 30 extends out a slight distance beyond the tip of the upper nib 38. This being the case, when the nibs are deflected in service, as is well shown, particularly in Figs. 3 and 10, the upper nib will be forced out so that its tip comes practically in line with that of the lower nib. Reference also particularly to Fig. 9 will show that the tip of the upper nib is serrated, or provided with a number of slots, so that the tip is virtually severed into a number of fine fingers. It is found that such slotting of the tip of the upper nib insures a better and more even discharge of the ink than would otherwise be the case when the nibs are deflected in service.

I claim:

1. In combination with an ink receptacle, an ink delivery tube outwardly extending from one end of the same, a slideable sleeve 25 mounted on the tube and provided with an inwardly extending needle adapted to close the end of the tube for restricting the flow of ink therefrom, and having the opposite faces of the sleeve flattened, and a pair of 30 nibs secured to the handle and provided with a pair of fingers adapted to engage the flattened faces of the sleeve to prevent rotation of the same.

2. In a device of the class described, the combination of an ink receptacle, an ink delivery tube outwardly extending from one end of the same, a slideable ink control member mounted on the tube, and having the opposite faces of the member flattened, and 40 a pair of nibs secured to the handle and provided with a pair of fingers adapted to engage the flattened faces of the sleeve to prevent rotation of the same.

3. In combination with a member, an ink delivery tube outwardly extending from the member, a slideable sleeve on the tube, an inwardly extending needle on the outer end of the sleeve adapted to close the outer end of the tube for restricting the flow of ink

therefrom, and means for actuating the sleeve on the tube for controlling the movements of the needle for controlling the opening of the ink delivery tube.

4. In a device of the class described, the combination of a receptacle, a pair of nibs 55 secured to the same, an ink delivery tube outwardly extending between the nibs, a slideable sleeve on the tube, an inturned needle on the sleeve adapted to control the opening of the tube, a lever pivoted to a 60 stationary portion of the device and adapted to control the movements of the sleeve, and a member on said lever adapted to contact one of the nibs and be actuated thereby, substantially as described. 65

5. In a device of the class described, the combination of a receptacle, a pair of nibs secured to the same, an ink delivery tube outwardly extending from the receptacle to a point between the nibs, a slideable sleeve 70 on the tube, provided near its rear end with a recess, a needle on the tube adapted to control the delivery of ink from the same, a lever pivoted to a stationary portion of the device and having a finger engaging the 75 recess of the sleeve and adapted to actuate the sleeve, and means for normally retaining the sleeve in position to force the needle against the opening of the tube to close the same, substantially as described. 80

6. In a device of the class described, the combination of a receptacle, a pair of nibs secured to the same, an ink delivery tube outwardly extending from the receptacle to a point between the nibs, a slideable member 85 on the tube, an inturned needle on said member adapted to control the flow of ink from the tube, a lever pivoted to a stationary portion of the device, an actuating connection from the lever to the sleeve, and a set- 90 screw on the lever adapted to contact one of the nibs and be actuated thereby, substantially as described.

OLAUS C. WOLD.
